UNITED STATES PATENT OFFICE.

WILLIAM TENBUSCH, OF PANA, ILLINOIS.

ACETYLENE-LANTERN.

1,152,991.

Specification of Letters Patent.

Patented Sept. 7, 1915.

Application filed May 14, 1914. Serial No. 838,610.

To all whom it may concern:

Be it known that I, WILLIAM TENBUSCH, a citizen of the United States, residing at Pana, in the county of Christian and State 5 of Illinois, have invented certain new and useful Improvements in Acetylene-Lanterns; and I do declare the following to be a full, clear, and exact description of the invention, such as will enable others skilled 10 in the art to which it appertains to make and use the same.

My invention relates to improvements in lanterns and has for its primary object to provide a device of this character employing 15 acetylene gas for fuel and constructed in the most simple manner consistent with its proper operation.

In carrying out the above end, I provide an acetylene generator having a gas burner, 20 a valve for controlling the amount of water fed to the carbide receptacle, a valve for controlling the gas discharged therefrom, both of said valves having laterally operating arms and a carrier for said generator, 25 said carrier having a receptacle provided for the reception of said generator and having a pair of bayonet slots adapted to receive said laterally swinging arms whereby the generator is retained in the carrier by said arms.

30 A secondary object of the invention is to render the device inexpensive in manufacture without sacrificing any of its advantages.

With the above objects in view, the invention resides in certain novel features of construction and combination herein described and claimed and shown in the drawings wherein:—

Figure 1 is a side elevation of a lantern 40 constructed in accordance with my invention; Fig. 2 is a horizontal sectional view taken upon the line 2—2 of Fig. 1; Fig. 3 is a vertical section taken along the plane of the line 3—3 of Fig. 2; Fig. 4 is a perspective view of the upper portion of the receptacle and the generator therein; and Fig. 5 is a detail vertical section showing parts illustrated in Fig. 3 on an enlarged scale.

In the accompanying drawings, I have 50 illustrated my invention as applied to a lantern which includes a generator receptacle 1 surrounded by an outwardly and upwardly inclining supporting flange, a suitable head or cap 2, globe 3 and guard 4 around said globe and connecting the receptacle 1 with the cap 2.

As clearly shown in Fig. 1, the upper end of the receptacle 1 as well as portions of the cap 2, are perforated, this construction being common to devices of this character. 60 It is to be further noted that the receptacle 1 is of cylindrical formation and has its upper edge provided with the outwardly extending flange which forms a support for the shield 4. This also is a common construction but said upper end of the receptacle 1 coats with fastening means in a manner to be described.

Disposed within the receptacle 1 and preferably resting on the lower end thereof, is 70 an acetylene generator 5, said generator being formed in an upper section 5' and a lower section 5'', said sections being united by means of forming interengaging screw threads on their meeting ends. As most 75 clearly shown in Fig. 3 a horizontal partition 6 extends transversely across the upper section 5', thus dividing the generator into an upper chamber 7 and a lower chamber 8, said upper chamber being adapted for the 80 reception of water while the chamber 8 receives the carbide from which the gas is to be generated.

For the purpose of controlling the amount of water fed into the receptacle 8 from the 85 receptacle 7, I provide a tube 9 which depends from the partition 6 and communicates with the chamber 7, the lower end of said tube being contracted as indicated at 10 to form a seat for a needle valve 11, the latter rising through the chamber 7, through a stuffing box 12 in the upper end thereof and being provided with a laterally swinging operating arm 13. As clearly shown in 90 Fig. 3, the upper end of said valve 11 is 95 threaded for engagement with internal threads formed on the stuffing box. Thus it will be seen that when the arm 13 is swung in the proper direction, the valve 11 will be raised out of contact with its seat thereby 100 allowing the desired amount of water to flow into the receptacle 8 or that all communication between the receptacles 7 and 8 may be obstructed.

Leading upwardly from the receptacle 8 105 through the partition 6 and the upper end of the chamber 7, is an upright gas discharge tube 14, the latter preferably having a screen 15 at its lower end while its extreme upper end, rising above the top of the 110 chamber 7, is externally threaded as most clearly seen at 16 in Fig. 5. Threaded upon

the upper threaded portion of said tube 14, is an internally threaded sleeve 17, the latter being provided with a transverse slot 18 and forming a support for a burner tip 19, 5 the lower end of which is spaced from the upper end of the tube 14. As clearly shown in Fig. 5, the slot 18 is disposed between the contiguous ends of the tube 14 and tip 19. Revolubly mounted within the space is a 10 partition 20 which is threaded on its exterior for engagement with the internal threads of the sleeve 17, said partition having a central opening 21, the material around said opening inclining upwardly and inwardly for the 15 purpose of forming a valve seat for a needle valve 22, the latter being rigidly secured within the tube 14 and being adapted to close the opening 21 when the partition 20 is rotated in the proper direction by means 20 of a suitable operating arm 23 which projects outwardly therefrom and through the slot 18.

By reference to the drawings, it will be seen that the valve operating arms 13 and 25 23 extend outwardly at substantially opposite points and that said arms project a considerable distance beyond the upright wall of the generator. This provision is made in order that said arms may act as locking 30 means for securing said generator within the receptacle 1, the upper edge of said receptacle being provided with a pair of bayonet slots 24 for their reception. Thus it will be seen that when the arms 13 and 23 are moved 35 in the proper directions, they will open or close their respective valves, as the case may be, and will simultaneously retain the entire generator within the receptacle 1 of the carrier. It will further be noted that, as 40 clearly shown in Fig. 2, said arms may be so positioned as to allow the generator to be readily removed from said receptacle.

From the foregoing description, taken in connection with the accompanying drawings, 45 it will be seen that these arms perform the two-fold function above mentioned and that this construction eliminates parts which

would be necessary provided other valve operating means were employed.

The above described construction thus 50 simplifies the manufacture of devices of this character and therefore decreases the cost of manufacturing the same, this being a salient feature in any article.

It may here be explained, although it will 55 be readily understood by those familiar with the art to which the invention relates, that the bayonet slots 24 and the portions of the carrier or receptacle 1 which overlie said slots, constitute keepers for engagement by 60 the horizontally swinging valve operating arms 13 and 23 and that other appropriate forms of such keepers might well be employed to equal advantage.

Having thus described my invention, what 65 I claim as new and desire to secure by Letters Patent is:—

In combination, a horizontal supporting plate having an opening, an upright tube having its upper end projected through and 70 above said opening and provided with external screw threads, a shoulder on the tube contacting with the lower side of the plate, an upright internally threaded sleeve whose lower end receives therein the upper externally threaded end of the tube and bears on the upper side of said plate, the threads in said sleeve being continued therein substantially throughout the length thereof, and said sleeve being provided with a horizontal slot, a centrally apertured partition 75 in the sleeve having external screw threads engaging the threads in the sleeve above the tube, a handle projecting from the partition through the slot in the sleeve, and a 80 fixed needle valve in the tube alined with the aperture in the partition.

In testimony whereof I have hereunto set my hand in presence of two subscribing witnesses.

WILLIAM TENBUSCH.
